UNITED STATES PATENT OFFICE.

CHARLES AUGUSTINE, OF HERMANN, MISSOURI.

WORK-FEEDING ATTACHMENT FOR SEWING-MACHINES.

1,156,339.

Specification of Letters Patent. Patented Oct. 12, 1915.

Application filed December 3, 1914. Serial No. 875,296.

To all whom it may concern:

Be it known that I, CHARLES AUGUSTINE, a citizen of the United States, residing at Hermann, in the county of Gasconade and State of Missouri, have invented certain new and useful Improvements in Work-Feeding Attachments for Sewing-Machines; and I do declare the following to be a full, clear, and exact description of the invention, such as will enable others skilled in the art to which it appertains to make and use the same.

This invention relates to improvements in work feeding attachments for sewing machines and more especially to feeding attachments for shoe closing machines.

The object of the invention is to provide a simply constructed work feeding attachment which is especially designed for use in connection with what is known on the market as the "Puritan" closing machine and which facilitates the feeding of the leather and prevents stretching or shifting thereof and feeds the leather in a uniform and regular manner.

With the above and other objects in view, the invention consists of certain novel features of construction, combination and arrangement of parts as will be more fully described and claimed.

In the accompanying drawings: Figure 1 represents a side elevation of a machine equipped with this improved attachment; Fig. 2 is a front elevation thereof; Fig. 3 is an enlarged side elevation of a portion of the machine, showing this improved attachment applied; Fig. 4 is a longitudinal vertical section taken on the line 4—4 of Fig. 3, showing the needle and the work feeding attachment in lowered inoperative position; Fig. 5 is a similar view taken on the line 5—5 of Fig. 3, showing the work feeder and needle in the act of being raised; Fig. 6 is a similar view showing the feeder and needle in raised operative position; Fig. 7 is a similar view showing the parts in the position which they assume when a stitch is being formed; Fig. 8 is a transverse section taken on the line 8—8 of Fig. 5; Fig. 9 is a similar view taken on the line 9—9 of Fig. 5; Fig. 10 is a detail perspective view of the work feeder constituting this invention.

In the embodiment illustrated, a leather sewing machine is shown having the usual overhanging arm 1 with a head 2 at one end. The usual work post 3 is disposed below this

head 2 and is equipped with a work plate 4 having the usual throat plate 5 therein.

Mounted for rocking or oscillatory movement in the post 3 is a feed rocker bar 6 through which the needle bar 7 and cast off bar 8 extend, the needle bar having a driving block 9 and the cast off bar a driving block 10. These blocks 9 and 10 operate in an opening 11 in the bar 6, being slidable in said bar. This feed rocker bar comprises an upright arm 12 having an apertured lateral extension 12' on its lower end adapted to be keyed to an oscillating shaft 12'', whereby the work is fed the length of the 70 stitch to be formed.

The work feeding attachment 15 which constitutes this invention, is shown in the form of a plate 16 having an angular opening 17 extending longitudinally therethrough and in which is slidably mounted the feeding member 18. This plate 16 is designed to be detachably mounted on the upright arm 12 of the feed rocker 6, being here shown screwed or bolted to one face of said 80 arm above the opening 11 therein.

The feeding member constitutes an angular body member 19 shaped to conform to the opening 17 in the plate 16 and to slide therein, said member 19 having a laterally 85 extending fork 20 at one end which is adapted to straddle the needle bar 7 above the block 9 thereof. Adjustably mounted on the other end of the body 19 is a head 21 having an offset feed rack 22 of a width slightly 90 less than the throat opening in the plate 5 and through which said feed rack is adapted to project and which is limited in its upward or outward stroke by a shoulder 23 which is formed on the lower end of bar 19 95 engaging the lower end of the casing 15. A coiled spring 25 connects the plate 16 with the upper end of the bar or body member 19 of the feeder and is designed to hold said feeder yieldably in retracted position, with 100 the rack 22 disposed below the upper face of the throat plate 5 normally out of contact with the work. This spring 25 also returns the feeder to lowered position after it has been raised by the needle bar driving 105 block 9 in a manner to be described.

In the operation of this feeding attachment, when the needle bar 7 carrying the driving block 9 is raised to its highest point, said block 9 will engage the forked foot 110 20 of the feeder bar 19 and raise said bar against the tension of the spring 25, there-

by projecting the rack 22 above the throat plate about three sixty-fourths of an inch more or less, according to the depth which it is designed the teeth of said rack shall engage the work to be fed. When this feeder is so projected, the teeth of the rack thereof will engage the leather or other work to be fed and raise it just a trifle sufficient to clear the throat plate 5 and permit the work to move over said plate without frictional engagement therewith and thus avoids stretching of the work. When the feeder has been lifted by the needle bar, the rocker 6 upon which the feeding attachment is fastened, will then be rocked back by means not shown, the length of the stitch which it is desired to make and this rocking of the member 6 will carry the feeding rack 22 with it and consequently feed the leather freely without any dragging thereof on the throat plate, which will avoid all possibility of the leather being stretched during the stitching operation. After the stitch has been formed and the needle bar 7 is lowered, the block 9 moving from under the forked foot 20 will permit the spring 25 to retract the bar 19, thus withdrawing the rack 22 below the throat plate out of engagement with the work where it will remain until the needle bar 7 is again raised for forming another stitch.

To apply this attachment to the Puritan machines already constructed, it is only necessary for a small portion of the post 3 to be cut away to afford space for the plate 16 to be properly mounted in the post and to permit it to rock with the feed bar 6 therein during the formation of the stitches.

From the above description, it will be obvious that when this attachment is employed, the leather will be uniformly and regularly fed without any danger of its being stretched or moved out of position.

I claim as my invention:

1. The combination with a sewing machine having an upright rocking bar with a needle bar extending therethrough, of a feeding attachment comprising a casing fixed to said rocking bar, a member slidably mounted vertically in said casing and having a forked foot straddling said needle bar above the projec-

tion thereon, and a head at the other end of said sliding bar having a feed rack offset therefrom.

2. The combination with a sewing machine having an upright rocking bar and a vertically reciprocatory needle bar, of a feeding attachment mounted on said rocking bar and comprising a casing having a member slidably mounted therein and provided at one end with work engaging teeth and at its other end with a needle bar engaging member, and yieldable means for retracting said slidably element and normally holding it in lowered position.

3. A work feeding attachment for sewing machines comprising a casing, means for attaching it to a support, a bar slidable in said casing and having a laterally extending forked foot at one end and an offset feed rack at its other end, and a coiled spring connected at one end with said bar and at the other end with said casing.

4. A work feeding attachment for sewing machines comprising a casing, means for attaching it to a support, a bar slidable in said casing and having a laterally extending forked foot at one end and an offset feed rack at its other end, and a coiled spring connected at one end with said bar and at the other end with said casing, said feed rack being adjustably mounted on said bar to vary its extent of projection.

5. A feeding attachment for sewing machines comprising an attaching casing, a bar slidably mounted in said casing and having a laterally extending forked foot at one end thereof and an offset feed rack at the other end, means on said bar for limiting its movement in said casing, and a coiled spring connecting said casing and bar for holding said bar normally in retracted position and for returning it to retracted position after it has been projected.

In testimony whereof I have hereunto set my hand in presence of two subscribing witnesses.

CHARLES AUGUSTINE.
